(57) **CLAIM**

The ornamental design for a docking station, as shown and described.

DESCRIPTION

FIG. 1 is a perspective view of a docking station showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front view thereof, shown with the stand in a closed position for use;

FIG. 10 is a rear view thereof, shown with the stand in a closed position for use;

FIG. 11 is a left side view thereof, shown with the stand in a closed position for use;

FIG. 12 is a right view thereof, shown with the stand in a closed position for use;

FIG. 13 is a top view thereof, shown with the stand in a closed position for use; and,

FIG. 14 is a bottom view thereof, shown with the stand in a closed position for use.

The dashed broken lines illustrate portions of the docking station and form no part of the claimed design.

1 Claim, 13 Drawing Sheets
